HANGER BRACKET FOR LANTERNS
OR THE LIKEDonald E. Loch, 3115 Jackson, Wichita, Kans. 67204
Filed June 26, 1967, Ser. No. 7,595

Term of patent 14 years

(Cl. D54—1)

FIG. 1 is a side elevational view of a hanger bracket for lanterns or the like;

FIG. 2 is a top view, a portion of the strap being omitted for ease of illustration;

FIG. 3 is a bottom view, the strap being omitted for convenience of illustration;

FIG. 4 is a side elevational view thereof, the lower brace being cut-away for convenience of illustration;

FIG. 5 is an elevational view from the right thereof; and

FIG. 6 is an elevational view from the left.

The broken lines in FIG. 1 are for illustration purposes only.

I claim:

The ornamental design for a hanger bracket for lanterns or the like, as shown and described.
